5 Claims. (Cl. 103—131)

This invention relates to rotary pumps in general and has specific reference to methods of arranging a rotary-drive volumetric pump consisting of a fixed structure comprising a substantially cylindrical chamber having formed therein orifices constituting the suction and delivery ports for the fluid, said chamber having arranged therein an impeller consisting of a plurality of movable members driven from a shaft imparting thereto a movement of rotation or circular translation.

Hitherto known pumps of this general type are characterized by a fixed output for a given velocity of rotation, and actually the only way of varying this output is by varying their velocity of rotation.

On the other hand, the movable members or impeller elements housed within the cylindrical chamber, that is, according to the pump type contemplated, the gears, the eccentric piston, etc., must be fitted with a relatively high degree of precision not only in relation to the inner cylindrical wall of this chamber but also in relation to the two lateral walls, so as to provide between the side faces of these movable members and these lateral walls a clearance sufficient to avoid any jamming but small enough to avoid abnormal leakage losses. Therefore, the movable members and the casing of these pumps must be machined to very close tolerances and their assembly constitutes a delicate operation.

This invention provides a method of arranging pumps of the general type set forth hereinabove, whereby the above-listed inconveniences are eliminated, this method being remarkable notably in that it consists in permitting the movement of translation of at least one of the walls defining the lateral limits of said cylindrical chamber, to provide, if desired, a direct fluid connection between said suction and delivery orifices, in order to vary the pump output at will.

Thus, the assembly method of this invention provides a volumetric pump wherein the output may be varied while maintaining its velocity of rotation to a constant value.

According to another feature of this invention, there is formed in the flange, cover plate or like member secured on the pump casing a recess constituting somewhat the lateral extension of the aforesaid cylindrical chamber, on at least one of the sides thereof, and a movable plate is housed in this recess in the vicinity of said one side, this movable plate being adjustable in position and constituting the aforesaid movable wall.

According to a further feature characterizing this invention, there is created in said chamber an adjustable relative vacuum tending to move said movable plate away from the relevant side wall of the chamber with a view to vary the pump output as a function of the value of this relative vacuum.

From the foregoing it will be readily understood that the fact of submitting the position of the movable plate and therefore the pump output to a pressure makes it possible to render the pump operation considerably more flexible and therefore to widen the field of its practical applications.

According to another characteristic feature of this invention resilient return means are provided for exerting on said movable plate a predetermined pressure counteracting the thrust created by said controlled vacuum and

2

tending to press said movable plate against the side wall of said pump chamber.

It will also be appreciated that with this construction it is possible not only to obtain an automatic play take-up 5 action resulting from the provision of the aforesaid resilient return means but also and therefore to simplify considerably the machining and assembling of the component elements of the pump.

This invention is also concerned with rotary-drive 10 volumetric pumps constructed according to the method broadly set forth hereinabove, that is, internal gear pumps, conventional gear pumps, swinging and guided vane rotary pumps, lobar pumps, eccentric pumps, etc.

Other features and advantages of this invention will 15 appear as the following description proceeds with reference to the accompanying drawings illustrated diagrammatically by way of example two typical forms of embodiment of the present invention. In the drawings:

FIGURE 1 is a diagrammatical cross section illustrating a gear pump, the section being taken along the line I—I of FIGURE 2;

FIGURE 2 is an axial section taken upon the line II—II of FIGURE 1 and showing the improvements constituting the subject matter of this invention;

FIGURE 3 is an axial section showing a pump with an impel cylinder which is arranged in accordance with the teachings of this invention;

FIGURE 4 is a front view of the pump shown in FIGURE 3, with the cover removed and the flange of the cylinder partly broken away;

FIGURE 5 is another axial section taken on line V—V of FIGURE 6 and illustrating a modified embodiment of the pump of FIGURE 3, and

FIGURE 6 is a section taken upon the line VI—VI of FIGURE 5.

In the form of embodiment illustrated in FIGURES 1 and 2 of the drawings the pump consists essentially of a casing or body 1 comprising a substantially cylindrical internal chamber 2 and two orifices or ports 3, 4 connected or adapted to be connected to the fluid intake and delivery pipes. Mounted within the cylindrical chamber 2 are the rotary members or impeller elements consisting in this example of two constantly meshing gears 5, 6 rotatably mounted about their shafts 7, 8, shaft 8 being operatively connected to the driving motor (not shown).

Secured on the two lateral faces of the casing 1 are two flanges 9, 10 constituting or receiving the bearings of the gear shafts 7, 8. The inner face of flange 10 is formed with a recess 11 constituting an extension, in the axial direction, of the aforesaid cylindrical chamber 2. Housed in this recess 11 is a movable plate 12 formed with a central orifice 13 fitting around an inner pin, boss, stud or like cylindrical projection 14 of flange 10 which has its axis parallel to the axes of rotation of the gears.

This movable plate 12 is slidably mounted on the inner pin 14 so that the latter acts both as a support and as a guide member. Of course, the movable plate 12 is also formed with bores 15, 16 necessary for the passage of the gear shafts 7, 8. This movable plate 12 is furthermore resiliently urged against the lateral face of casing 1 by means of coil springs 17 or like means housed in cavities 18 of flange 10 and bearing on said movable plate through the medium of domed heads 19 slidably fitted in these cavities.

65 A pipe 20 provided with a valve 21 connects the recess 11 with the outside or with any closed space kept at a pressure inferior to that of recess 11, or with any other suitable device.

This pump operates as follows:

When priming the pump, that is, before a substantially constant pressure is obtained in recess 11, the springs or like resilient means 17 urge the movable plate 12 against

the outer face of casing 1, thus preventing any direct communication between the suction and delivery ports 3, 4 for the fluid. Under continuous operating conditions, a constant pressure is obtained in recess 11 which tends to press also the movable plate 12 against the casing, this pressure depending on the induction and delivery pressure values or manometrical level.

When the valve 21 is opened in order to connect the recess 11 with a space kept at a pressure lower than that prevailing in this recess 11, a pressure reduction is observed in recess 11 and this pressure reduction causes the plate 12 to perform a movement of translation away from the casing on the pin 14. Under these circumstances the suction and delivery ports are in direct intercommunication through the recess 11, thus determining a reduction in the pump output.

Of course, the springs 17 are so calculated as to exert on the plate 12 a pressure of predetermined value which is a function, notably, of the desired output variation to be applied to the pump.

The space to which pipe 20 is connected may be for instance a tank subjected to the atmospheric pressure. Pipe 20 may also be connected to the suction side of the pump.

By modifying the position of the control member of valve 21 it is obvious that the pump output may be modified at will.

FIGURES 3 and 4 illustrate a pump of the type wherein an impeller cylinder or eccentric piston comprising at its end a flange extending at right angles to its axis is mounted eccentrically on a rotary shaft and adapted to perform oscillatory movements inside an annular cavity of the casing which is closed by said flange and provided with a radial partition, the ports 28a, 28b of the suction and delivery ducts of the pump opening on either side of said partition.

The pump comprises essentially a casing 22 formed with a bore 23 and on which is mounted a fixed body 24 having a cylindrical central portion 25 coaxial with the bore 23. The cylindrical portion 25 and bore 23 form together an annular cavity 26 provided at its upper portion with a fixed radial partition 27 on either side of which open the ports 28a, 28b of the suction and delivery ducts of the pump.

One of these ducts (the delivery duct or the suction duct, according to the direction of rotation of the pump) is shown at 28. The movable member or piston of the pump comprises a cylindrical portion 29 and a flange 30 extending at right angles to the axis of cylinder 29. The flange 30 carries in its central portion a hollow hob 31 threaded on a socket or sleeve 32 secured eccentrically on a shaft 33. A flexible blade 34 mounted between said socket and shaft maintains the eccentricity of the socket and piston assembly and resiliently urges the cylinder 29 against the wall of bore 23.

The cylinder is formed with a radial slot 29a for reserving the location of the fixed partition. The flange also carries, on its face opposite to that carrying the cylinder 29 and substantially in front of the aforesaid radial slot, a roller 35 displaceable between the two guide faces of the casing (only one of these faces 36 being visible in FIGURE 3). It is known that the rotation of shaft 33 produces an oscillatory motion of the piston of which the cylindrical portion 29 forms in the annular recess 26 two chambers 26a, 26b, 26a being the suction chamber and 26b the delivery chamber when the pump rotates in the direction indicated by F, and that it is the variation in volume of these two chambers that produces the fluid suction and delivery.

Secured on the front face 22a of casing 22 is a cover 37 forming with the casing a chamber 38 adjacent to the annular cavity 26 and separated therefrom by the flange 30 housed in turn in chamber 38. This flange 30 is urged against the front face 22a by springs or like means such as 39 located in recesses such as 40 of the cover 37 and

bearing on said flange through the medium of spring-loaded studs or heads 39a slidably mounted in said recesses.

A pipe 41 provided with a control valve 42 connects the chamber 38 with the outside. The cover 37 is so designed that the dimensions of chamber 38 are sufficient to permit a limited movement of translation of the piston and therefore of flange 30 in a direction parallel to the axis of rotation of the pump. This chamber is of substantially cylindrical configuration and its diameter is substantially greater than that of flange 30.

FIGURES 5 and 6 illustrate a modified embodiment of the pump shown in FIGURES 3 and 4; this alternate embodiment is particularly adapted for installations distributing fluids in air-free circuits. It is known in fact that in certain circuit arrangements the liquid output must be determined with a relatively high degree of precision, for example by means of meters, and that therefore any air or gas circulation likely to alter the data given by these meters must strictly be avoided.

In FIGURES 5 and 6 a tank 43 is mounted directly on the pump casing 22 so as to constitute therewith a unitary structure. The fluid to be pumped flows by gravity to the tank 43 through a pipe fitting 44. The suction port 28 of the pump is connected to an intake pipe 45 opening substantially in the vicinity of the bottom of tank 43. The chief interest of this arrangement lies in the fact that air is prevented from penetrating into the circuit. This intake pipe 45 may also act as a baffle and permits if desired a complementary extraction of any residual gas from the liquid. The delivery duct 28' is connected to another pipe fitting 46. The chamber 38 communicates with the tank 43 through a passage 47 provided at its end with a regulating device consisting for example of a double balanced valve 48, 48' controlled by a float 49 connected through a rod 50 to said valve. If desired, a cam or like device 51 controlled from the outside by means of a handle 52 and co-acting with a cam follower or like member 53 rigid with the rod 50 may be provided, whereby the float may be locked in a predetermined position to keep the valve in its open position. In the pipe fitting 46 a spring-loaded valve 54 may be mounted for closing the distributor circuit. The tank 43 is also provided with an orifice 55 for venting same to the atmosphere. The liquid contained in tank 43 is drawn by the pump up the intake pipe 45 and then forced through the pipe fitting 46 to the distributor circuit.

If the momentary quantity of liquid drawn by the pump exceeds the liquid output fed to the tank 43 through the inlet fitting 44, air will penetrate into the tank through the venting orifice 55. The float 49 will descend and thus open the double valve 48, 48', thus creating a discharge and a relative vacuum in chamber 38. As a result, the piston will be displaced and the pump output reduced accordingly. There is obtained automatically a condition of equilibrium whereby the pump output is adjusted exactly as a function of the float level in tank 43.

If the supply of liquid is discontinued, the float descends to a limit position whereat the pump output is reduced completely to zero. It will be noted that the residual pressure under zero output conditions is considerably lower than the adjustment pressure of the spring-loaded or calibrated valve 54. The output is stopped positively when the liquid level in the tank exceeds that of the inlet orifice of the intake pipe 45. Thus, the pump will never draw in air and therefore it cannot deliver air with the liquid.

Although the form of embodiment intended for avoiding pumping air through the pump has been shown and described only with reference to an eccentric impeller pump, it will be noted that it is applicable directly to other types of rotary-driven volumetric pumps arranged according to the method of this invention.

Of course, many modifications may be brought to the

device described herein, without departing from the spirit and scope of the invention.

Although the present method of construction of the invention has been illustrated in connection with external gear pumps and cylindrical impeller pumps, it will be readily understood by those conversant with the art that it is also applicable to internal gear pumps, Roots pumps, vane pumps, eccentric pumps, etc.

Of course, the present invention should not be construed as being limited to the few forms of embodiment illustrated and described herein as many modifications may be brought thereto without departing from the spirit and scope of the invention as set forth in the appended drawings.

What I claim is:

1. A volumetric pump with rotary drive comprising a casing which forms a cylindrical cavity, a radial fixed partition in said cavity, a cover secured to said casing, said cover having internal blind hole means, a recess constituting an extension of said cavity and limited by said cover, a movable cylinder having a radial slot for receiving the location of said fixed partition located in said cavity, said cylinder dividing the latter into a suction and a delivery chambers, a suction port connected to said suction chamber, a delivery port connected to said delivery chamber, a power shaft, means eccentrically secured on said power shaft for imparting to said movable cylinder a movement of circular translation combined with an oscillatory motion, a flange formed solid with said movable cylinder and located in said recess, said flange constituting a separating wall between said cavity and said recess, the assembly comprising said flange and said movable cylinder being displaceable in translation parallel to the axis of said power shaft to permit a direct interconnection between said suction and delivery chambers, spring-loaded studs slidably mounted in said blind hole means and projecting in said recess for resiliently urging said flange toward said cylindrical cavity, and duct means opening in said recess to connect the latter to a space kept at a controlled pressure, said duct means comprising a control valve means for adjusting at will the pressure prevailing in said recess, the output of the volumetric pump being thus a function of the value of said pressure.

2. A pump as claimed in claim 1 comprising a tank fed with the liquid to be pumped, an intake pipe connected to said suction port and having an inlet orifice opening near the bottom of said tank and a duct connected to said recess and opening in said tank, said duct being provided with a regulating device responsive to the liquid level in said tank.

3. A pump as claimed in claim 1 wherein a locking member adapted to be actuated from the outside is provided for holding said regulating device in a predetermined fixed position.

4. A pump as claimed in claim 1 wherein said delivery port of said pump is connected to an outlet pipe provided

with a non-return valve urged to its open position by calibrated spring means, said valve being adapted to close said outlet pipe before the liquid level in said tank attains the level of the inlet orifice of said intake pipe.

5. A volumetric pump with rotary drive comprising a casing which forms a cylindrical cavity and a recess constituting an extension of said cavity, movable means in said casing, said movable means dividing said cylindrical cavity into a suction and delivery chambers, a suction port connected to said suction chamber, a delivery port connected to said delivery chamber, a power shaft to drive said movable means, a plate located in said recess said plate constituting a separating wall between said cavity and said recess, said plate being displaceable in translation parallel to the axis of said power shaft to permit a direct interconnection between said suction and said delivery chambers, calibrated return means located within said recess for resiliently urging said plate toward said cylindrical cavity, a tank fed with the liquid to be pumped, an intake pipe connected to said suction port and having an inlet orifice opening near the bottom of said tank, a duct connected to said recess and opening in said tank, said duct being provided with a regulating device responsive to the liquid level in said tank, an outlet pipe connected to said delivery port and provided with a nonreturn valve urged to its open position by calibrated spring means, said valve being adapted to close said outlet pipe before the liquid level in said tank attains the level of the inlet orifice of said intake pipe.
